UNITED STATES PATENT OFFICE.

WILLIAM E. WOODARD, OF FOREST HILLS, NEW YORK, ASSIGNOR TO FRANKLIN RAILWAY SUPPLY COMPANY, OF NEW YORK, N. Y., A CORPORATION OF DELAWARE.

LATERAL-MOTION DEVICE FOR DRIVING BOXES.

Application filed November 6, 1920. Serial No. 422,248.

To all whom it may concern:

Be it known that I, WILLIAM E. WOODARD, a citizen of the United States, residing at Forest Hills, in the county of Queens and 5 State of New York, have invented certain new and useful Improvements in Lateral-Motion Devices for Driving Boxes, of which the following is a specification.

This invention relates to lateral motion 10 devices for driving or axle boxes for locomotives and other railway vehicles with or without trucks. The invention has the same general objects and purposes and is intended to meet the same general conditions 15 as the construction shown in United States Letters Patent No. 1,181,194, issued to Riegel and myself on May 2, 1916, which may be taken as an exemplification of the lateral motion appliances in general service.

20 In the construction referred to, however, for reasons which will further appear, the driving boxes are approximately from one and one-half to two times their normal length which requires a corresponding increase in the length of the axle journals, and heavy cross ties are employed between the driving boxes and between the driving springs. As a result, the arrangement is expensive to manufacture and to apply and is 25 difficult of application to existing locomotives because it involves many changes in adjacent parts.

30 One of the prime objects of my invention is to provide a simple and inexpensive device which may be readily applied to new and old locomotives with little or no change in adjacent parts, and in which the driving boxes and journals are of normal length, the heavy cross ties between driving boxes and, 35 in some instances, the connecting members between driving springs eliminated.

Still another object of the invention is to 40 provide an arrangement in which only one driving box deflects laterally at a time, simplifying centering.

45 My invention also contemplates an improved arrangement whereby the driving springs or other load transmitting means and the lateral motion resisting means cooperate to maintain the load central on the driving boxes which is of great practical importance.

The foregoing, together with such other objects as may hereinafter appear, or are

incident to my invention, I obtain by means 55 of a construction, the preferred embodiments of which are illustrated in the accompanying drawings, wherein:

Fig. 1 is a cross section taken through a locomotive frame adjacent a pair of drivers 60 and their axle and illustrating the general application of my invention, the section being taken on the line 1—1 of Fig. 2 on a reduced scale; Fig. 2 is a section taken on the line 2—2 of Fig. 1 on an enlarged scale; 65 Fig. 3 is a section on the line 3—3 of Fig. 2; Fig. 4 is a fragmentary plan view of Fig. 2; Fig. 5 is a section through modification of a detail of my improvements; Fig. 6 is a section on the line 6—6 of Fig. 5; Fig. 7 70 is a section through another detail modification; Fig. 8 is a section on the line 8—8 of Fig. 7; and Figs. 9 and 10 are diagrammatic views illustrating how certain of the parts operate.

75 As herein exemplified, the invention is applied to a locomotive, the frame A of which is of the standard bar type, with its two side members spaced apart the maximum distance available under the necessary limitations imposed by the width between driving wheel hubs. Each side frame member includes, in so far as the driving box receiving portions thereof are concerned, the top rail 7, bottom rail 8, and vertical pedestal jaws 85 9 which are connected by the usual pedestal ties 10. The axle for a pair of drivers 11 is indicated by the reference letter C, while the driving boxes therefor are indicated by the letter B. The boxes B are fitted in the 90 pedestals to have vertical play therein by any standard shoe and wedge means, 12, and 13, respectively, or their mechanical equivalents; and they have lateral motion by virtue of the fact that their outer and inner 95 flanges 14 and 15 (see Fig. 4) are spaced apart a sufficient distance to provide a predetermined clearance between the outer flanges and the shoes and wedges, this clearance being determined in each instance by 100 such factors as length of rigid wheel base, type of locomotive, and track curvature. The portion of the locomotive weight carried by the boxes is transmitted through the driving springs D in the manner now to be 105 described.

Each driving spring rests on a saddle E having two depending, spaced legs 16 and

17 for transmitting load to the axle box B at opposite sides of the frame, at different points lengthwise of the axle C, the former being the longer and resting directly on the 5 driving box in a seat or pocket 18. These legs straddle the top rail 7 and the saddle is free to ride up and down and to rock slightly. The shorter leg 17 rests upon a seat 19^a formed in the horizontal ledge, arm 10 or leg 19 of a centering lever or rocker member F which is in the nature of a bell-crank. The lever member at each end is provided with a depending leg or arm 20, and adjacent each arm it is formed with a rounded 15 bearing portion 21, which is received in a correspondingly formed seat 22 provided in the laterally extending lug 23, preferably formed integral with the box B. It will be understood that there are two such lugs 23, 20 one on each side of the inner end of the box. By this arrangement, the centering lever is fulcrumed on the box. The lever cannot shift lengthwise of the box by reason of the legs 20 and shoulders 24 fitting over the lugs 25 23 and it cannot shift transversely of the box because the weight carried holds the bearing portions 21 in their seats in the lugs.

Cross ties G extend crosswise of the frame and connect corresponding pedestal jaws of 30 the two side members of the frame, being secured to the jaws in any preferred manner. The cross ties are provided with lugs 25 against which the depending arms 20 of each centering lever bear.

, 35 The parts are shown in normal position in Figs. 3 and 4, from inspection of which it will be seen that the wear face of the boxes abuts against the hubs of the drivers; the arms 19 of the centering levers rest on the 40 top of the box; the arms 20 are practically in working contact or engagement with the lugs 25 on the cross ties of the frame; and there is a clearance space between the outer flanges 14 of the box and the shoes and 45 wedges, indicated by the letter x in Fig. 4.

Assuming that the lateral thrust in curving is in the direction indicated by the arrow in Fig. 3, the boxes on that side will shift laterally inward until the flanges 14 50 abut against the shoes and wedges. As they shift inwardly, their lever arms F will be rocked about their fulcrum points because the arms 20 abut against the immovable lugs 25 on the cross ties. The arms 20 thus rock 55 outwardly and the arms 19 upwardly, lifting the inside legs 17 of the saddles and causing the saddles to rock slightly on the end of the outside legs 16. The lever arms thus directly carry a portion of the load 60 and, therefore, resist the lateral motion of the boxes, the weight automatically returning the boxes to proper center when there is no longer a lateral thrust or pressure. The boxes on the other side do not deflect 65 laterally under the conditions noted, and

the axles push therethrough the amount of the lateral deflection, this occurring very readily since lateral deflection only occurs when the locomotive is in motion and the axles are rotating. When the thrusts are in 70 the opposite direction, the operation of the parts on the other side is the same as just described.

The operation of the parts will be best understood from inspection of Figs. 9 and 75 10. In Fig. 9, the relation of the boxes and centering means to the vertical center line o of the frame, when the parts are in normal position, is shown. When lateral motion takes place, the upper end of the saddles 80 does not move inwardly, for the inward movement of the box, the lever, and the lower ends of the saddles is compensated for by the lifting movement imparted by the lever. The resultant of these two movements is approximately a rotative movement of the saddle on a center intermediate the spring and the top of the box. The top of the saddle thus does not move inwardly, but the saddle tilts slightly from the vertical 85 as indicated in Fig. 10. The springs, therefore, are not displaced to any appreciable extent, and at most merely accommodate themselves to the very slight inclination of the top surface of the saddle from the horizontal. The relation of the springs to the 90 rigging is thus substantially not disturbed.

The length of the lever arm is to be determined in the first instance by the load carried and the thrusts liable to be encountered.

To prevent tilting of the springs when a relatively large amount of lateral motion may be required, I provide arrangements such as shown in Figs. 5 and 6, and Figs. 7 105 and 8. In the arrangement of Figs. 5 and 6, I interpose the ends of a cross member 26 between the springs and the saddles F, such ends being rounded as indicated at 27 so as to permit the saddles to rock thereon 110 without tilting of the springs as the compound movement of the saddle takes place. The manner in which the saddles and cross members are interfitted will be clear on inspection of the figures.

In the construction of Figs. 7 and 8, a stirrup 30 is interposed between the saddle and the spring, such stirrup having a seat for the spring and having a sliding fit on the top rail 7 of a frame member so as to permit 115 of vertical play. As the saddle is tilted and laterally shifted it rocks on the rounded surface 31 of the stirrup and the only motion the latter has is a vertical one, which does not tilt the spring. To prevent the stirrup 120 from wearing the rail, a wear piece 33 is inserted.

One of the important advantages incident to all the forms of my invention shown, is that the load on the driving boxes is at 130

all times maintained substantially central. When the parts are in the normal position illustrated in Fig. 3, the load is transmitted centrally because the legs 16 of the saddles 5 bear directly on one end of the boxes while the legs 17 bear on the arms 19 of the centering levers, such arms in turn resting on the boxes at the opposite ends thereof. When lateral motion of the boxes takes place, this 10 relation is not disturbed for the legs 16 still bear directly on the boxes and, while the arms 19 no longer lie on top of the boxes, load is transmitted to the opposite ends of the boxes through legs 17 and the centering 15 levers as the latter rock on their fulcrum points on the boxes. The load is thus substantially equally distributed by the cooperation of the saddles and levers. In the construction in the aforesaid patent, the load 20 transmitting means does not bear directly on the box in most of the forms shown but on transverse cross ties which transmit the load to the boxes through lateral resistance rockers, a construction which involves ex- 25 tension of the length of the driving boxes so that the rockers or other members will bear substantially on the middle of the boxes. In the construction of Figs. 13 and 14 of said patent, while the saddles rest di- 30 rectly on the boxes, the lateral motion resisting lever 17 does not cooperate to maintain the load central.

I claim:

1. In a railway vehicle, the combination 35 of an axle box having lateral motion, a load transmitting means, and a leverage means interposed between the box and the load transmitting means offering resistance to the lateral motion of the box.

2. In a railway vehicle, the combination 40 of an axle box having lateral motion, a load transmitting means, and a leverage means fulcrumed on the box and interposed be- 45 tween it and the load transmitting means offering resistance to the lateral motion of the box.

3. In a railway vehicle, the combination 50 of an axle box having lateral motion, of weight transmitting means bearing on the box, and leverage means also bearing on the box and interposed between the box and the weight transmitting means so as to come into operation on lateral motion of the box to resist such motion.

4. In a railway vehicle, the combination 55 of an axle box having lateral motion, of a load transmitting spring, a saddle for the spring bearing on the box, and means inter- 60 posed between box and saddle for resisting lateral movement of the box.

5. In a railway vehicle, the combination 65 of an axle box having lateral motion, of a load transmitting spring, a saddle for the spring bearing on the box, and a lever ful- crumed on the box and interposed between

box and saddle for resisting lateral movement of the box.

6. In a railway vehicle, the combination with an axle box having lateral motion, of a weight transmitting means bearing on the 70 box, and means bearing on the box and adapted to bear against the weight transmitting means and receive load therefrom on lateral motion of the box to resist such motion.

7. In a railway vehicle, the combination with a frame, of an axle box having lateral motion with respect to the frame, a weight transmitting means bearing on the box, and gravity means at an end of the box operable 80 on lateral motion of the box for resisting lateral movement of the box.

8. In a railway vehicle having an axle box with capacity for lateral motion, the combination of a load transmitting means and 85 a separate lateral motion resisting means, said means cooperating to maintain the load central on the box and offering resistance to lateral motion throughout the range of such motion.

9. In a railway vehicle having an axle box with capacity for lateral and vertical motion, the combination of a load transmitting means and a separate lateral motion resisting means, said means cooperating to 95 maintain the load central on the box and offering resistance to lateral motion throughout the range of such motion.

10. In a railway vehicle the combination of an axle, wheels therefor, a pair of boxes 100 for the axle having lateral motion independently of one another, and centering means for the boxes.

11. In a railway vehicle the combination of an axle, wheels therefor, a pair of boxes 105 for the axle having lateral motion independently of one another, and a centering means for each box.

12. In a railway vehicle having a box for 110 an axle capable of lateral movement, a centering member consisting of a bell crank adapted to bear on said box and to receive load from the vehicle.

13. In a railway vehicle having a box for 115 an axle capable of lateral movement, a bearing seat on said box, and a centering lever journaled in said seat.

14. A railway vehicle lateral motion device comprising, in combination with the axle box, load transmitting means with portions for transmitting load to the axle box at different points lengthwise of the axle, and means interposed between one of such portions and the box for raising said portion and rocking said load transmitting means on the other such portion when the box is shifted by lateral thrust, and returning the box under actuation by the portion so raised when such thrust is relieved.

15. A railway vehicle lateral motion de-

- vice comprising, in combination with the axle box and the vehicle frame, load transmitting means with portions for transmitting load to the axle box at different points 5 lengthwise of the axle, and a rocker fulcrumed on the box with one of its arms actuated by one of such portions of said load transmitting means and its other arm engaged with the frame.
16. A railway vehicle lateral motion device comprising, in combination with the axle box and the vehicle frame, a saddle straddling the frame above the axle box with legs for transmitting load to the latter 10 at opposite sides of the frame, and means operatively interposed between saddle and axle box for yieldingly resisting lateral shifting of the box by lateral thrust and returning the box when such thrust is relieved.
17. A railway vehicle lateral motion device comprising, in combination with the axle box and the vehicle frame, a saddle straddling the frame above the axle box with 15 legs for transmitting load to the latter at opposite sides of the frame, and means interposed between one of such legs and the box for raising said leg and rocking the saddle on the other leg when the box is shifted by lateral thrust, and returning the box under actuation by the leg so raised when such thrust is relieved.
18. A railway vehicle lateral motion device comprising, in combination with the 20 axle box and the vehicle frame, a saddle straddling the frame above the axle box with a leg bearing on the latter outside the frame, and a lever fulcrumed on the box inside the 25 frame with one of its arms beneath the other saddle leg and its other arm engaged with the frame.
19. In a railway vehicle having an axle box with capacity for lateral motion, the combination of load transmitting means and lateral motion resisting means, the load transmitting means bearing on the box and the lateral motion resisting means also bearing on the box and operating on the load transmitting means when lateral motion takes place, whereby the load transmitting means and the lateral motion resisting means cooperate to maintain the load central on the box.
20. In a railway vehicle, the combination of an axle box having lateral motion, load transmitting means bearing on the box, and separate lateral motion resisting means interposed between the load transmitting means and the box and always operating to return the parts to normal position.
21. In a railway vehicle having an axle box with capacity for lateral motion, the combination of load transmitting means for transmitting load to the box, and lateral motion resisting means also transmitting load to the box, said lateral motion resisting means also operating on the load transmitting means when lateral motion takes place, whereby the load transmitting means and the lateral motion resisting means cooperate to maintain the load central on the box.

In testimony whereof, I have hereunto signed my name.

WILLIAM E. WOODARD.
